(57) **CLAIM**

The ornamental design for a flow control valve, as shown and described.

DESCRIPTION

FIG. 1 is a top, front and left-side perspective view of a flow control valve showing a first embodiment of our new design; FIG. 2 is a bottom, rear and left-side perspective view thereof;

FIG. 3 is a front view thereof;

FIG. 4 is a rear view thereof;

FIG. 5 is a top plan view thereof;

FIG. 6 is a bottom plan view thereof;

FIG. 7 is a left side view thereof;

FIG. 8 is a right side view thereof;

FIG. 9 is a top, front and left-side perspective view of a flow control valve showing a second embodiment of our new design;

FIG. 10 is a bottom, rear and left-side perspective view thereof;

FIG. 11 is a front view thereof;

FIG. 12 is a rear view thereof;

FIG. 13 is a top plan view thereof;

FIG. 14 is a bottom plan view thereof;

FIG. 15 is a left side view thereof; and,

FIG. 16 is a right side view thereof.

The broken lines are included for the purpose of illustrating portions of the flow control valve and form no part of the claimed design.
